UNITED STATES PATENT OFFICE.

JOHN A. PILCHER, OF ROANOKE, VIRGINIA.

COUPLER ATTACHMENT.

Application filed September 1, 1922, Serial No. 585,771. Renewed June 26, 1928.

This invention relates to railway cars and draft gears therefor.

One object of the invention is to provide a coupler attachment rotatively secured to a coupler and to a cushioning mechanism in such a manner as to permit angling of the coupler relative to the attachment and angling of the attachment relative to the cushioning mechanism. In the usual form of coupler attachment used heretofore, which has been a yoke, bending stresses are set up in the attachment when the pull on the coupler is out of line with the axis of the cushioning mechanism. In my invention the coupler attachment, which comprises a pair of links, being rotatively secured to the cushioning mechanism, the axis of the coupler and the coupler attachment will remain in line during pulling and this bending stress removed.

20 A further object of the invention is to provide a coupler attachment which may be interlocked with a coupler and a cushioning mechanism by movement of the coupler and the cushioning mechanism relative to the attachment.

A still further object of the invention is to provide a coupler attachment in which the usual rear follower block is dispensed with, thereby providing a lighter and cheaper construction and yet one as strong as the yoke which has been usually employed heretofore.

30 My invention also consists in the cooperation and arrangement of parts which I shall hereinafter describe and claim.

35 This application is a continuation in part of my co-pending application filed April 12, 1921, Serial Number 462,082.

In the accompanying drawings Figure 1 is a plan showing an attachment embodying my 40 invention in position in the underframing of a car; Figure 2 is an elevation thereof; Figure 3 is a plan showing the method of positioning the attachment, coupler, and cushioning mechanism after they have been locked together before applying to car.

45 Referring to the drawings, the coupler attachment is comprised of an upper link 1 and a lower link 2, each of which has a vertically disposed slot 3 extending therethrough of substantially the same width from end to end of the link. The coupler butt 4 on its top and bottom surfaces is provided with circular extensions 5 each of which has laterally extending lugs 6 arranged at right angles to the longitudinal axis of the coupler. The cushioning mechanism 7 is equipped with

trunnions 8 and laterally extending lugs 9 similar to the trunnions 5 and lugs 6 on the coupler butt. The slots 3 in the ends of the links 1 and 2 are arc-shaped and provide 60 bearings 10 for the trunnions 5 and 8 on the coupler butt 4 and cushioning mechanism 7, respectively. Thus substantial pulling bearings are provided between the coupler and the links 1 and 2 and between the links 1 and 2 and the cushioning mechanism 7, and at the same time the coupler may angle relative to the links and the links relative to the cushioning mechanism. The rear face of the coupler butt 4 and the forward face of the follower 70 block 11 preferably have corresponding arc-shaped faces to permit the stresses of buffing to be transmitted directly from the coupler to the cushioning mechanism, regardless of the particular position to which the coupler 75 may angle laterally with respect to the links. The tangential surface leading away from the arc-shaped forward face on the follower 11 also serves to guide the coupler butt back into position after it has been pulled away 80 from the follower during draft.

The coupler, cushioning mechanism, links and front follower are assembled before placing in the car. The coupler and cushioning mechanism are placed side by side with the 85 lugs 6 and 9 lined up so that the links can be passed over them at the same time. The coupler is then turned until its axis coincides with the axis of the links. Then the follower is placed with its forward face against 90 the rear face of the coupler butt and turned at an angle to its normal position as shown in Fig. 3. The cushioning mechanism is then turned until its forward face comes in contact with the rear face of the follower 95 and from this position the cushioning mechanism and follower may be forced snugly into their normal position, placing the cushioning mechanism under slight compression.

100 After the mechanism has been assembled it is then elevated into position on the car. Beneath the coupler butt and the rear end of the cushioning mechanism is a bottom plate of any preferred form, detachably connected to the car frame, which forms a bearing for 105 the lower lugs 6 and 9 on the coupler butt and cushioning mechanism, respectively, and holds the corresponding upper lugs near the top plate 12, thereby limiting the vertical movement of the mechanism.

110 The rear face of the forward draft sill stops 13 are tapered slightly, as are the cor-

responding faces of the follower 11 to allow the edges of the follower 11 to enter the space clear of the edges of the stops and thereby permit the easy application of the mechanism

5 to the car.

Thus I have invented a coupler attachment which is relieved from the usual lateral bending stresses to which a U-shaped yoke is ordinarily subjected when the pull is out of line 10 with the axis of the yoke, one of fewer parts and of lighter weight than the usual yoke form and one which may be secured to the other members of the draft mechanism by relative movement therewith.

15 It is my intention to cover all modifications of the invention falling within the spirit and scope of the following claims:

I claim:

1. In a device of the character described, a 20 coupler attachment comprising upper and lower links, a coupler the butt thereof having a slot and projection engagement with the forward ends of the links and also having an 25 arc-shaped rear face, a cushioning mechanism including a friction member, said member having a slot and projection engagement with the backward ends of the links, a fol-

lower having an arc-shaped forward face cooperating with the rear face of the coupler butt, the follower being capable of rotation 30 about said coupler butt to permit the easy insertion of the cushioning mechanism between said links.

2. In a device of the character described, a 35 coupler attachment comprising a pair of links, a coupler and a cushioning mechanism, trunnions on the coupler butt and on the main portion of the cushioning mechanism engaging said links and permitting, respectively, rotary movement between the coupler and 40 links and between links and cushioning mechanism, and means for holding the links on said trunnions.

3. In a device of the class described, a 45 coupler attachment comprising slotted upper and lower links, a coupler having a pulling connection in slots in the forward ends of said links, and a cushioning mechanism having trunnions on the top and bottom surfaces thereof engaging said upper and lower 50 links and providing rotary and longitudinal movement between said coupler and cushioning mechanism.

JOHN A. PILCHER
